DESIGN FOR A PLATE OR ANALOGOUS ARTICLE

Kisaburo Kato, San Francisco, Calif.

Application December 15, 1937, Serial No. 73,637

Term of patent 7 years

To all whom it may concern:

Be it known that I, Kisaburo Kato, a subject of the Emperor of Japan, residing at San Francisco, in the county of San Francisco and State of California, have invented a new, original, and ornamental Design for a Plate or Analogous Article, of which the following is a specification, reference being had to the accompanying drawing, forming a part thereof.

The figure is a plan view of a plate or analogous article, showing my new design.

The design shown is continued throughout the border of the plate or the analogous article.

I claim:

The ornamental design for a plate or analogous article, substantially as shown and described.

KISABURO KATO.
